(57) **CLAIM**

The ornamental design for a headphone, as shown and described.

DESCRIPTION

The patent or application file contains at least one drawing executed in color. Copies of this patent or patent application publication with color drawings will be provided by the Office upon request and payment of the necessary fee.

FIG. 1 is a perspective view of a headphone showing the new design;

FIG. 2 is a front elevational view of the headphone;

FIG. 3 is a rear elevational view of the headphone;

FIG. 4 is a top plan view of the headphone;

FIG. 5 is a bottom plan view of the headphone;

FIG. 6 is a left side elevational view of the headphone;

FIG. 7 is a right side elevational view of the headphone; and,

FIG. 8 is a front elevational view with the headphone in a rotated position.

The broken lines and ghosted areas depict environment that forms no part of the claimed design.
